UNITED STATES PATENT OFFICE.

ADAM KLINGBACK, OF EMMETT, IDAHO.

POWER-HAMMER.

1,353,347.

Specification of Letters Patent.

Patented Sept. 21, 1920.

Application filed April 25, 1917. Serial No. 164,471.

To all whom it may concern:

Be it known that I, ADAM KLINGBACK, a citizen of the United States, residing at Emmett in the county of Gem, State of Idaho, have invented certain new and useful Improvements in Power-Hammers; and I do hereby declare the following to be a full, clear, and exact description of the invention, such as will enable others skilled in the art to which it appertains to make and use the same.

This invention is an improvement in power hammers and has particular reference to a foot operated mechanism for actuating the hammer.

An object of the invention is to provide an improved mechanism for obtaining the greatest amount of force to the blow of the hammer by the application of the least amount of power and, to this end, use is made of a plurality of simultaneously operated rocking members to one of which is connected a hammer supporting member actuated by the movement of said rocking members.

Another object is the provision of an improved mounting for the hammer in the supporting member therefor whereby the head thereof may be reversed and said hammer removed when desired.

A further object is the provision of a device of this character which is simple in construction, easy to manufacture and effective in carrying out the purpose for which it is designed.

The inventive idea involved is capable of receiving a variety of mechanical expressions, one of which, for the purpose of illustrating the invention, is shown in the accompanying drawings wherein:—

Figure 1 is a side elevation of the device constructed in accordance with the invention and showing the hammer in normal or inoperative position.

Fig. 2 is a similar view showing the parts in the position assumed at the conclusion of the striking movement of the hammer.

Fig. 3 is a front elevation of the device.

Fig. 4 is a rear elevation thereof.

Fig. 5 is a bottom plan view.

Fig. 6 is a vertical longitudinal section.

Fig. 7 is a section on the line 7—7 of Fig. 8.

Fig. 8 is a section on the line 8—8 of Fig. 1.

The invention is illustrated, in the accompanying drawings, in what is now believed

to be its preferred form and comprises a main frame consisting of a rectangular base 10 having an anvil 11 secured at one end thereof and provided adjacent its base with 60 a vertical slot 12, the purpose of which will later appear. The sides of the frame preferably consist of front and rear uprights 13 and 14 respectively, arranged in converging relation and connected at their upper ends by 65 the cross pieces 15.

A plurality of rocking members, 16, 17 and 18 are disposed one above another between the sides of the main frame and are pivoted at their outer ends therein alternately or in staggered relation, each member consisting of a substantially U-shaped frame. The lowermost frame 16 has its ends pivoted at 19 adjacent the lower ends of the rear uprights 14 and said frame is provided upon its 70 forward end with an extension 20 terminating in a pedal 21 which projects through and beyond the slot 12 in the anvil whereby the same may be readily depressed by the operator. The next superposed or intermediate frame 17 has its ends secured to a shaft 22 rotatably mounted in the front uprights 13 and the sides of said frame 17 are connected intermediate their ends to the intermediate portions of the sides of the frame 80 16 by links 23 so that a rocking movement, imparted to the lower frame 16 will be transmitted to the frame 17. The uppermost frame 18 is secured to the rotatable shaft 24, journaled in the uprights 14 90 adjacent the upper ends thereof and the sides of said frame 18 adjacent the shaft 24 are connected by links 25 to the sides of the frame 17 contiguous to the bight portion thereof. 95

The hammer supporting member 26 is preferably mounted between the sides of the main frame and journaled for oscillatory movement in the cross pieces 15 and connected to said supporting member are 100 adjacent ends of normally closed helical or coil springs 27 which extend in diverging relation and have their other ends connected to the bight portion of the upper rocking frame 18. From the foregoing description 105 it will be apparent that when the foot pedal 21 is depressed the frames 16, 17 and 18 will be simultaneously rocked about their pivots and through the springs 27 the supporting member 26 will be oscillated. When 110 said supporting member is returned to its normal position, in a manner to presently

appear, the momentum thereof will, after the frame 18 has reached its uppermost limit, expand said springs until such momentum is overcome. Therefore the subsequent contraction of the springs will increase the initial momentum of the hammer supporting member at the beginning of its next downward or power stroke thus making it possible for the operator to depress 10 the pedal with the least amount of exertion.

The mechanism for returning the hammer supporting member 26 to its normal position preferably comprises an oscillatory lever 28 secured, intermediate its ends, to a shaft 29 journaled in the uprights 14 adjacent the shaft 24 and the upper end of said lever is connected to said member 26 by a link 31. The lower end of said lever has one end of a link 30 secured thereto, the other end of which is connected to a rod or bar 33 having a plurality of openings 34 therein, any one of which is adapted to receive one end of a large coil spring 35 the other end of which is secured to the base of 25 the anvil 11. The purpose of the several openings 34 in the rod 33 is to permit of regulating the tension of the spring 35 when desired. It will be apparent that when the foot pedal 21 is depressed and the supporting member 26 makes a power stroke the same will, through the link 31, pull the upper end of the lever 28 forwardly and thus expand the spring 35 so that upon the release of pressure upon the foot pedal said 35 spring will retract and cause the supporting member 26 to return to its normal position at which time the expansion of the coil springs 27 occurs, as previously described.

The hammer head is of any suitable construction and has its handle or helve 36 mounted in a socket 37 in the member 26, each end of said socket being provided with ring members 38 and 39, the former having oppositely disposed notches 40 therein for 40 normally receiving the ends of a transverse pin 41 carried by the inner end of the handle of said hammer. This pin 41 is normally retained in engagement with said notches by means of the coil spring 42 mounted in 45 said socket and exerting an outward pressure upon said handle. The ring member 39 at the upper end of the socket is provided with a semi-circular slot 43 the upper edge of which is provided at its ends with 50 notches or recesses 44 which normally receive the transverse pin 45 also carried by the handle of the hammer so that when said handle is in normal position the same will be prevented from returning relative to 55 the supporting member or, in other words, relative to the longitudinal axis of said socket. However, should it be desired to reverse the head of the hammer, it is only necessary to depress the handle against the 60 tension of the spring 42 until the pins 41

and 45 are disengaged from their respective notches, after which said handle may be rotated about its longitudinal axis for a half revolution until the pin 45 contacts the opposite end of the slot 43. Upon releasing pressure on the handle of the hammer the spring 42 will then force the same upwardly and cause the pins 41 and 45 to again engage their respective notches. It will be readily apparent that by withdrawing the pins 41 and 45 the hammer may be removed and replaced.

What is claimed is:—

1. In a power hammer, the combination of a main frame, a hammer support pivoted 80 therein, a hammer carried thereby, a pedal also pivoted in said main frame, a plurality of rocking frames supported by said main frame and connected to each other and to the pedal and support to transmit a power 85 stroke to the hammer, means connected to said support for returning the same to normal position after the conclusion of said power stroke, and a normally contracted spring between said support and one of said 90 rocking frames yielding at the conclusion of one stroke and then contracting to increase the efficiency of the next.

2. In a power hammer, the combination of a main frame, a hammer supporting 95 member mounted for oscillation therein, a hammer carried thereby, and a plurality of rocking frames arranged in superposed relation, pivoted at their outer ends to said main frame and projecting alternately inward from their pivots, the frames being connected with each other and to said supporting member whereby to operate the same to transmit a power stroke to said hammer.

3. In a power hammer, the combination of a main frame, a hammer supporting member mounted for oscillation therein, a hammer carried thereby, an oscillatory lever carried by said main frame and connected at 110 one end to said supporting member, resilient means connected to the other end of said lever for returning said supporting member to normal position at the conclusion of a power stroke of said hammer, and means 115 connected to said supporting member for increasing the initial momentum of the former at the beginning of a power stroke.

4. In a power hammer, the combination of a main frame, a hammer supporting member mounted for oscillation therein, a hammer carried thereby, an oscillatory lever carried by said main frame and connected at one end to said supporting member, resilient means connected to the other end of said 120 lever for returning said supporting member to normal position at the conclusion of a power stroke of said hammer, and coil springs connected to said supporting member for increasing the initial momentum of 130

the former at the beginning of a power stroke.

5. In a power hammer, the combination of a main frame, a hammer supporting member mounted for oscillation therein, a hammer carried thereby, a plurality of rocking frames disposed one above another and having their outer ends alternately pivoted to said main frame, said frames being connected to each other and the uppermost connected to said supporting member whereby to operate the same to transmit a power stroke to the hammer, and a pedal carried by the lowermost of said frames for rocking 15 the same to impart a similar motion to the other frames.

6. In a power hammer, the combination of an oscillatory hammer supporting member having a socket, a hammer whose helve has one end rotatably mounted therein whereby the hammer head may be reversed, ring members carried by said supporting member and having notches therein, and pins carried by said hammer and normally engaging said 25 notches to prevent rotary movement of said hammer.

7. In a power hammer, the combination of an oscillatory supporting member having a socket, a hammer having one end rotatably mounted in said socket and movable longitudinally therein to permit of said rotation, and a spring in said socket and engaging said hammer for yieldably resisting said longitudinal movement and normally preventing said rotary movement. 30 35

8. In a power hammer, the combination of an oscillatory supporting member having a socket, a hammer whose helve has one end mounted in said socket and movable rotatably and longitudinally therein to permit 40 of said rotation, said member having notches and said helve having pins, and a spring in said socket holding said notches and pins in engagement for resisting said longitudinal movement and normally preventing said rotary movement. 45

In testimony whereof, I affix my signature in the presence of two witnesses.

ADAM KLINGBACK.
